(57) **CLAIM**

The ornamental design for a hand therapy and aligning device, as shown and described.

DESCRIPTION

FIG. 1 is a front, isometric view of a hand therapy and aligning device showing my new design;

FIG. 2 is a back, isometric view of a hand therapy and aligning device;

FIG. 3 is a top view of a hand therapy and aligning device;

FIG. 4 is a bottom view of a hand therapy and aligning device;

FIG. 5 is a front, perspective view of a hand therapy and aligning device;

FIG. 6 is a rear, perspective view of a hand therapy and aligning device;

FIG. 7 is a rear, perspective view of a hand therapy and aligning device; and,

FIG. 8 is an exploded view of the hand therapy and aligning device, shown in FIG. 7.

Only the solid lines and surfaces with shading are claimed. The broken lines depict portions of the hand therapy and aligning device that form no part of the claimed design.
